RUG AND THE METHOD OF MAKING SAME

Alexander C. Rindskopf, Chicago, Ill., assignor of
one-half to Herbert O. Shults, Chicago, Ill., and
one-half to Emma Rindskopf, Wilmette, Ill.

Application October 19, 1931, Serial No. 569,630
Renewed July 28, 1933

7 Claims. (Cl. 2—278)

An object of this invention is to provide a new form of floor rug and a method of making the same.

Another object is to provide tufts for making the rug which are assembled in a convenient form for use, as well as ropes or bundles of fibers from which the tufts can readily be formed during the process of making the rug.

Another object is to provide a convenient form 10 of needle for attachment to these tufts or ropes for insertion of the same in the rug.

These and other objects, as will hereinafter appear, are fully described in the following specification and shown in the accompanying 15 drawing, in which—

Figure 1 is a partial front elevation of the base fabric used for making the rug with some of the tufts assembled therein;

Fig. 2 is a detail of a rope or warp from which 20 tufts can be made;

Fig. 3 is a similar view of one of the tufts ready for insertion in the rug;

Fig. 3^a is a similar view showing a modified form of tuft;

Fig. 4 is a section through an edge of a rug 25 showing the tufts inserted therein, some of the tufts having been hammered down or otherwise flattened out;

Fig. 5 is a similar view showing a center portion of the rug made up of two overlapping portions of the base fabric with one of the tufts 30 in process of the insertion;

Fig. 6 is an enlarged view of a tuft placed in a needle by means of which it is to be inserted in a rug;

Fig. 7 is a developed view of the needle showing how it can be formed from a sheet of metal;

Fig. 8 is an enlarged section on the line 8 35 of Fig. 6; and

Fig. 9 is a view similar to Fig. 2 showing a modified form of rope for making the tufts.

The embodiment illustrated comprises a rug made up with a base fabric 10 which is preferably of a loosely woven fabric, such as burlap, or linen, which has printed on one side a series of markings 11 to indicate points in the fabric through which the tufts are to be inserted. These markings may have indications associated therewith, such as numbers which are 45 shown in Fig. 1 for indicating the color of the tuft which is to be inserted at each point. A legend identifying the numbers and the colors which they indicate may be printed on the fabric itself, or may be printed upon a card which 50 accompanies the fabric, or is attached thereto.

The tufts 12, as shown in Fig. 3, consist of a bundle of fibers or threads of any suitable material, such as wool, cotton, silk, rayon, asbestos, metal, or mixtures of the same. These bundles can be made in the form of long strands 60 or bundles 13 of these yarns or fibers, twisted or untwisted as shown in Fig. 2, the strands 13 being firmly bound at regular intervals by means of metal wire rings 14 which hold the fibers so firmly that they can scarcely be withdrawn from the tufts without breaking the fibers. Between these fastenings are secured pairs of binding members 15 which hold the fibers together, but more loosely than the metal rings 14. 65

Having formed a bundle of these fibers in this way, they can then be transversely severed along the dotted lines of Fig. 2 to form the individual tufts 12, which have a centrally disposed metal ring or other rigid binding member 14, and a 70 relatively loose binding member 15 at one end of the tuft. To insert this tuft into the rug it is first placed in the end of a needle 16 which preferably has three spring-like portions 17, 18 and 19, the portions 17 and 19 being longer than 75 the portion 18, and having inwardly turned prongs 20 which serve to catch and hold the binding member 15.

When the tuft is so placed in the needle, the needle 16 is inserted through the base fabric 10 80 at one of the points indicated and drawn through until it assumes the position shown in Fig. 5, wherein the tuft 12 has passed half its length through the fabric 10 so that the ring binder 14 is substantially in the plane of the fabric. The 85 brushing or spreading of the outer end of the tuft will resist its being drawn any further through, and the operator then pulls on the needle so as to remove the binding member 15 from the closed end of the tuft and immediately causes the tuft to 90 spread, as shown at 12^a (Figs. 4 and 5). By hammering these tufts on a flat surface they spread still more assuming the position 12^b of Fig. 4, wherein the adjacent ends of the tufts have 95 spread until they form substantially a solid surface. These tufts can then be removed from the base fabric only with considerable difficulty, the hammering serving also to force the base fabric more firmly around the tufts. 100

While the binding member 14 is preferably 105 made of a non-corrosive material, such as rust-proof steel, it will be understood that it may also be formed of thread or cord, and may be either tied about the waist of the tuft or it may be sewed therethrough. Also the binding member 15 may 110

be thread or the like which is applied only tightly enough to accomplish the desired purpose of drawing the tuft through the base fabric, after which it should be readily removable by an additional pull.

One method of treating the outer edge of the base fabric 10 is shown at 10^a, Fig. 4, in which this edge is turned back upon itself and the tufts at that point inserted through both portions of the base fabric. Likewise in Fig. 5 is shown how two separate portions of the base fabric may be united in this way by means of the tufts. If desired, this may be previously stitched as at 21 to give it additional strength. In this way it is possible to extend the rug as it is made, thereby permitting use of a base fabric 10 which is much smaller than the rug size desired, so that the operator is not required to handle such large pieces while the rug is being made.

For example, the base fabric could be laid out and each section of it completed except for that part where the overlap comes, and this could then be stitched together as at 21 and then the tufts in the overlapping portion could then be inserted, thereby completing that portion of the rug. This method of making the rug dispenses with the necessity for a frame, since the operator can hold the rug in the lap or on a table during the entire process of assembly.

A modified form of the rope from which the tufts are formed is shown in Fig. 9. This consists of a rope 22 which is bound as before by means of firm binding members 14^a, but in this form there are no intermediate binding members. A piece of this rope, say three feet in length, is attached as before to the needle 16 and is drawn through the base fabric 10^b until the last binding member 14^a is substantially in the plane of the fabric 10^b, after which the rope is severed along the line 22^a. The two portions on both sides of the line 22^a are then spread as previously described.

In Fig. 3^a is shown a modified form of the tuft 12^c which is firmly bound at its middle by a member 14^b as before but is held at one end by a binding member 23 which may be of paper or fabric. This is inserted in a needle 16 as in Fig. 6 for insertion in the fabric 10, and this binding is removed by the needle after the tuft is inserted. For convenience, the binding 23 is made twice as long as shown in Fig. 3^a, and is severed in the middle when the rope is cut, as indicated in Fig. 2.

It may be desirable for bathrooms and the like to use a sheet of rubber, as a base, instead of the fabric 10. Tufts of rubber or rubberized fibers or threads, or tufts of sponge rubber stippled at the center may be threaded through this sheet in the manner above described. Also an asbestos base fabric and tufts of asbestos wool may be used to make a fireproof rug, as for use in front of a fireplace. Combinations of any of these materials may also be employed, including fine metal threads or wires.

These tufts can also be used for decorative effects in clusters or scattered and inserted in the

same way in ladies' wearing apparel, or hats, in draperies, bedspreads, table scarfs, and the like.

While I have shown and described but a few embodiments of my invention, it is to be understood that it is capable of many modifications. Changes, therefore, in the construction and arrangement may be made which do not depart from the spirit and scope of the invention as disclosed in the appended claims.

I claim:

1. In combination, a base fabric and tufts each comprising a group of fibers bound together near their centers, said tufts extending through said base with their bound portions engaging the base and their extremities spread to form wearing surfaces.

2. A tufted fabric comprising a base fabric, and tufts each comprising a group of fibers bound together near their centers by a ring, said tufts extending through said base fabric with said ring engaging the base and the extremities of said tufts spread to form wearing surfaces.

3. A tufted fabric comprising a base fabric made up of two overlapping fabric sections, and tufts each comprising a group of fibers bound together near their centers and extending through the overlapping sections with their bound portions engaging therewith, the extremities of said tufts being spread, whereby to secure said sections together and provide wearing surfaces.

4. The method of making a tufted fabric comprising forming a tuft of fibers, binding the same at a point near the middle of the tuft, inserting the fibers of one end of the tuft in a needle, forcing said needle with the tuft therein completely through a base fabric, whereby the bound portion of the tuft is engaged and held by the base fabric as the needle is withdrawn from the fabric.

5. The method of making a rug tufted fabric comprising forming a tuft of fibers, binding the same at a point near the middle of the tuft, inserting and securing the fibers of one end of the tuft in a needle, forcing said needle with the tuft therein through a base fabric, removing the needle from the tuft, and spreading the end of the tuft so held.

6. The method of making a rug tufted fabric comprising forming a mushroom-shaped tuft of fiber which is securely bound near its middle and bound near one end, inserting the bound end of the tuft in a needle, passing the needle and bound end of the tuft through a base fabric, removing the needle and end binding from the end of the tuft, and spreading the fibers of the end of the tuft.

7. The method of making a rug tufted fabric comprising forming a rope or fibers bound at regular intervals, forming an opening in a base fabric, drawing said rope through said opening until the last point at which it is bound is in the plane of the fabric, and cutting the fibers so as to form ends of the fibers of substantially equal length on both sides of the fabric.

ALEXANDER C. RINDSKOFF.
